UNITED STATES PATENT OFFICE.

PAUL HAMMES, OF TRIER, GERMANY.

BOOT BLOCK.

Application filed September 29, 1926, Serial No. 133,544, and in Germany December 11, 1925.

The present invention relates to boot blocks of the type in which the front block is composed of two parts hinged to one another and has for its object the provision of means whereby the component parts of a boot block, such as the lower sole part and the upper instep part are rendered replaceable, so that the necessity for having several boot blocks for different sizes of boots—
5 as is especially the case for children's boots—is avoided.

This object is attained according to the invention by the provision of a vertical spindle threaded in a lug on a vertical bar and having at its lower end a fork-shaped guiding member which encloses the said bar and slides along the latter when the spindle is operated, the said bar being provided at its lower end with a tongue member which is held in an easily detachable manner by means of projections in slots arranged in the rear end of the upper part of the front block. The said fork-shaped member rests in slots formed in the rear end of the upper part of 20 the front block and co-operates with said vertical spindle in such a manner that when the said spindle is rotated the fork-shaped member and with it the upper part of the front block is raised or lowered. The front 25 block is held tightly in position on the bar by means of a screw co-operating with the tongue member.

One constructional form of the invention will now be described by way of example 30 with reference to the accompanying drawings, Figs. 1 to 3, in which:

Fig. 1 is a side view of the device with the front block indicated by dotted lines,

Fig. 2 is a partial view of the bottom of 40 the block and its fastening attachments viewed from below, and

Fig. 3 is a back view looking towards the block.

The lower or sole part 1 and the upper or 45 instep part 2 of the front block are hinged to one another by means of the hinge 3. The vertical bar 4 is provided at its lower end with a tongue 17 which is furnished with lateral projections 18 the said tongue 50 with its projections resting in a groove 19 with transverse slots formed in the rear end of the lower part 1 and being held in place in said slots by means of a screw and washer as hereinafter described.

55 The vertical bar 4 is provided at its upper end with a lug 7 through which a vertical

spindle 6 is threaded. The spindle 6 carries a nut at its lower end on which nut a fork-shaped member 15 rests. The fork-shaped member 15 engages in slots formed transversely to the groove 19 in the upper part 2 of the front block.

When the spindle 6 is rotated the fork shaped member 15 and with it the upper part 2 of the front block is raised or lowered 60 as required for the purpose of adjusting the heightwise stretching of the upper of the boot. The limbs of the fork-shaped member 15 rest on either side of the bar 4, so that when the spindle is rotated the fork-shaped 65 member 15 slides up or down along the said bar.

The bar 4 is provided with a rearwardly projecting clip carrying a pivot pin 12 upon which a two-armed lever 11 is pivotally 70 mounted. The lower end 14 of the lever 11 forms the heel block whilst the upper end of said lever is provided with a fork 10 in which a nut 9 is rotatably mounted. Through this nut 9 a horizontal spindle 8 is 75 threaded, which spindle 8 is hingedly and rotatably connected at its front end with the upper part of the bar 4.

When the horizontal spindle 8 is rotated, the heel block 14 is caused to move to the left or right as required for the purpose of 80 adjusting the lengthwise stretching of the boot.

On the underside of the lower part 1 of the front block a circular hollow 20 is 85 formed over the end of the groove 19. This hollow 20 serves for the reception of a washer 21 of greater width than the groove 19, through which washer a screw 22 passes 90 which serves for holding the tongue of bar 95 4 firmly in position in the front block.

It will be clear from the preceding description that the front block can be very easily and speedily removed from the other parts and replaced.

100 I claim:

1. In boot stretching and widening blocks of the type in which the front block is composed of two parts hinged to one another at the front end the combination of: a vertical bar, projecting members on said bar at its lower end, said projecting members engaging in slots in the rear end of the lower part of the front block, a lug forwardly projecting from the upper end of said bar, a vertical spindle threaded in said lug, and a removable fork-shaped member arranged in 105 110 115

slots in the rear end of the upper part of the front block and co-operating with said spindle for the purpose of enabling the upper and the lower part of the front block to be adjusted with relation to one another, the front block being easily detachable from all the other parts, substantially as described.

2. In boot stretching and widening blocks of the type in which the front block is composed of two parts hinged to one another at the front end the combination of: a vertical bar, a forwardly extending tongue on said bar engaging in a vertical groove in the rear end of the lower part of the front block, lateral projections on said tongue engaging in slots in the rear end of the lower part of the front block, an easily detachable screw member passing through the bottom of the lower part of the front block and holding said tongue in position, a lug forwardly projecting from the upper end of said bar, a vertical spindle threaded in said lug, a fork arranged in slots in the rear end of the upper part of the front block and co-operating with said spindle for the purpose of enabling the upper part of the front block to be raised or lowered by the rotation of said spindle, a nut threaded on the lower end of said spindle and holding said fork in position on said spindle, a rearwardly projecting clip on said bar, a double armed lever pivotally mounted in said clip, the lower end of said lever forming the heel block, a fork-shaped member arranged at the upper end of said lever, a nut rotatably mounted in said fork-shaped member, and a horizontal spindle hingedly and rotatably attached at its front end to the upper part of said bar and screwed through said nut, the front block being easily detachable from all the other parts, substantially as described.

3. In boot stretching and widening blocks

of the type in which the front block is composed of two parts hinged to one another at the front end, the combination of: a vertical bar, a forwardly extending tongue on said bar engaging in a vertical groove in the rear end of the lower part of the front block, lateral projections on said tongue engaging in slots in the rear end of the lower part of the front block, an easily detachable screw member passing through the bottom of the lower part of the front block and holding said tongue in position, a lug forwardly projecting from the upper end of said bar, a vertical spindle threaded in said lug, a fork arranged in slots in the rear end of the upper part of the front block and co-operating with said spindle for the purpose of enabling the upper part of the front block to be raised or lowered by the rotation of said spindle, a nut threaded on the lower end of said spindle and holding said fork in position on said spindle, a rearwardly projecting clip on said bar, a double armed lever pivotally mounted in said clip, the lower end of said lever forming the heel block, a fork-shaped member arranged at the upper end of said lever, a nut rotatably mounted in said fork-shaped member, and a horizontal spindle hingedly and rotatably attached at its front end to the upper part of said bar and screwed through said nut, the front block being easily detachable from all the other parts, substantially as described.

In testimony whereof I have hereunto set my hand.

PAUL HAMMES.
